UNITED STATES PATENT OFFICE.

OSCAR F. ERICKSON, OF BERKELEY, AND RICHARD H. BRADSHAW, OF OAKLAND,
CALIFORNIA.

LETTER-BOX ALARM AND INDICATOR.

No. 882,752.

Specification of Letters Patent. Patented March 24, 1908.

Application filed September 5, 1907. Serial No. 391,444.

To all whom it may concern:

Be it known that we, OSCAR F. ERICKSON and RICHARD H. BRADSHAW, citizens of the United States, residing, respectively, at 5 Berkeley and Oakland, in the county of Alameda and State of California, have invented new and useful Improvements in Letter-Box Alarms and Indicators, of which the following is a specification.

10 The object of the present invention is to provide means for automatically giving notice at a distant point that a letter or other article has been deposited in a letter box or other receptacle.

15 The invention is capable of use in all dwelling houses, and is of especial value for use in flats, or in connection with rural delivery boxes, which are generally placed at considerable distance from the residences to 20 which they belong.

In the accompanying drawing, Figure 1 is a broken front elevation of the apparatus; Fig. 2 is a broken vertical section thereof; Fig. 3 is a front view of the alarm, showing 25 the visible signal displayed when a letter has been deposited in the box; Fig. 4 is a similar view of the alarm, the rotary contact maker having been removed therefrom; Fig. 5 is a rear view of the rotary contact maker; Fig. 6 30 is a front view of the same; Fig. 7 is an edge view of the same; Fig. 8 is an enlarged broken perspective view of the alarm.

Referring to the drawing, 1 indicates an ordinary letter box to which our invention 35 is applied. Upon the inner surface of this box is secured an insulating plate 2, upon which are secured upper and lower spring contacts 3, 4, and a spring wire contact maker 5 is secured upon said plate in the 40 middle as shown at 6. The ends of said wire are guided by bars 7 so that when either end is moved toward the front of the box it is adapted to be brought into contact with the corresponding spring contact 3 or 45 4.

Said ends are connected by cords 8, 9, the upper 8 to the hinged lid 10 of the opening through which letters are dropped into the box, and the lower 9 to the door 11 by which letters are removed therefrom. It 50 results that, when either the lid or the door is open, contact is made with one or the other of said spring contacts.

12 indicates a battery, to one pole 13 of which leads a wire 14 from the point of attachment 6 of the spring wire contact maker

5, while a wire 15 leads from the other pole 16 of the battery to a binding screw 17 of the alarm. From two other binding screws 18 and 19 lead wires 20 and 21 to the two spring contacts 3, 4. From the middle binding screw 17 a wire 22 leads to electro-magnets 23 of an alarm 24, a wire 26 then leading from said magnets to the contact post 27 of the alarm, which is mounted on insulating material 28, secured on the plate 29 which 35 supports the alarm. The outer binding screws 18, 19 are connected respectively by wires 38, 39, with two semi-circular contact plates, 30, 31, over which can travel a rotary contact maker 32, having on the rear side a 40 spring tongue 33, adapted to contact with one or the other of said contact plates. To rotate said contact maker 32 it is formed on its edge with ratchet teeth 34 adapted to be engaged by a spring pawl 35 connected with 45 the vibrator 36 of the electric alarm.

The operation is as follows. Supposing that the rotary contact maker 32 is in the position corresponding to Fig. 1 of the drawing, in which position the spring tongue 33 on its rear side is in contact with the plate 30 on the right, and that when in this position the lid of the letter box is raised, then the following circuit is closed. From the pole 16 of the battery by wire 15 to the binding post 17, by 50 wire 22 through the electro-magnets 23 by wire 26 to the post 27, then to the vibrating arm 36, then from said arm in two branches, one through the plate 29 to the central forwardly projecting part 29' of said plate 29, on 55 which is mounted the rotary contact maker 32, and another through the spring pawl 35, thus passing through both branches to said rotary contact maker 32, then by the spring tongue 33 at the rear of the spring contact maker to 60 the semi-circular contact plate 30 on the right, then by a wire 38 to the binding screw 18 on the right, then from said binding screw by wire 20 to the upper spring contact 3, then by the spring wire 5 to the central point 65 6, then by wire 14 to the other pole of the battery. This circuit being closed, the magnet is thereby energized, the vibrating arm 36 is withdrawn from the post 27, and the contact is thereby alternately broken, and closed 70 in the usual manner. At every vibration of the arm, the rotary contact maker is advanced, which movement only requires a small fraction of a second after the opening 75 of the door, so that the contact maker im- 80

mediately engages the plate 30. This motion continues so long as the spring tongue 33 on the contact maker engages the plate 30. When the rotary contact has rotated through 5 half a revolution, which brings the word "Mail" on its front face opposite to the opening 42 in the outer case 43 of the alarm mechanism, the spring tongue 33 moves from off the contact plate 30 on the right and on to 10 the contact plate 31 on the left. Since the door 11 of the letter box has not been opened, the contact of the spring tongue 33 with the plate 31 on the left does not close any circuit, and therefore, this circuit is permanently 15 broken until said door is opened. On the opening of the door the circuit is now again closed, and the rotary contact maker rotates, so that a blank surface appears in the casing, 20 said contact maker continuing to rotate until the spring tongue 33 has again come into contact with the contact plate 30 on the right. The box is now again in condition for giving an alarm by the opening of the lid when a letter or other matter is deposited.

25 It is to be observed that the alarm will not ring continuously by leaving the lid open, or by leaving the door open, but only so long as both the lid and the door are opened at the same time.

30 The device can be attached to any form of letter box which is provided with a movable lid covering the opening for the letters and a door for removing the letters.

We claim:

35 1. An apparatus of the character described, comprising a letter box having a lid for closing the opening through which the letters are deposited, and a door for removing said letters, an electro magnetic alarm, a battery 40 therefor, a rotary contact maker, a wire lead-

ing from one pole of said battery to the electro-magnet of said alarm, two semi-circular contact plates from which said rotary contact maker can alternately contact as it rotates, means for rotating said contact maker simultaneously with the operation of said alarm, conductors leading in parallel from said plates to the other pole of the battery, having breaks therein, contacts for closing the respective breaks, and means for closing the contacts by opening the lid and door respectively, substantially as described.

2. An apparatus of the character described, comprising a letter box having a lid for closing the opening through which the letters are deposited, and a door for removing said letters, an electro-magnetic alarm, a battery therefor, a rotary contact maker, a visible signal device carried by said rotary contact maker, a wire leading from one pole of said battery to the electro-magnet of said alarm, two semi-circular contact plates with which said rotary contact maker can alternately contact as it rotates, means for rotating said contact maker simultaneously with the 65 operation of said alarm, conductors leading in parallel from said plates to the other pole of the battery, having breaks therein, contacts for closing the respective breaks, and means for closing the contacts by opening 70 the lid and door respectively, substantially as described.

In testimony whereof we have hereunto set our hands in the presence of two subscribing witnesses.

OSCAR F. ERICKSON.
RICHARD H. BRADSHAW.
